To all whom it may concern:

Be it known that I, THOMAS J. STEARNS, of Boston, in the county of Suffolk and State of Massachusetts, have invented a new and original Design for Carpets, of which the following is a specification:

The nature of my design is fully shown in the accompanying photographic illustration.

The design consists chiefly in the groups or bouquets of lilies *a a*, arranged on a background containing other minor floral designs, as shown.

I claim—

The design for carpets, substantially as shown and described.

In testimony whereof I have signed my name to this specification in the presence of two subscribing witnesses this 17th day of December, 1878.

THOMAS J. STEARNS.
